Primary Examiner — Randall Gholson(74) *Attorney, Agent, or Firm* — Edell, Shapiro & Finn, LLC(57) **CLAIM**

The ornamental design for a video conference system endpoint, as shown and described.

DESCRIPTION

FIG. 1 is a front perspective view of a video conference system endpoint;

FIG. 2 is a rear perspective view of the video conference system endpoint of FIG. 1;

FIG. 3 is a front elevation view of the video conference system endpoint of FIG. 1;

FIG. 4 is a rear elevation view of the video conference system endpoint of FIG. 1;

FIG. 5 is a first side elevation view of the video conference system endpoint of FIG. 1;

FIG. 6 is a second side elevation view of the video conference system endpoint of FIG. 1;

FIG. 7 is a top plan view of the video conference system endpoint of FIG. 1; and,

FIG. 8 is a bottom plan view of the video conference system endpoint of FIG. 1.

The broken lines depict portions of the video conference system endpoint that form no part of the claimed design.
